INVENTOR.

BY

James J. Sheehan, Jr.
ATTORNEY.

UNITED STATES PATENT OFFICE.

JOHN J. McDERMOTT, OF NEW ORLEANS, LOUISIANA.

ENVELOPE.

Application filed January 27, 1921. Serial No. 440,444.

To all whom it may concern:

Be it known that I, JOHN J. McDERMOTT, a citizen of the United States, residing at New Orleans, in the parish of Orleans and 5 State of Louisiana, have invented new and useful Improvements in Envelopes, of which the following is a specification.

My present invention pertains to envelopes, and it contemplates the provision in 10 an envelope of means whereby when the same has been sealed, it may be readily and easily opened, and this without liability of tearing or otherwise injuring the contents of said envelope.

15 The invention further contemplates the provision of means whereby the string that I employ to open the envelope will be at all times ready for use.

The invention in all of its details will be 20 fully understood from the following description and claim, when the same are read in connection with the drawings, accompanying and forming part of this specification, in which:

25 Figure 1 is a side elevation of my novel envelope and showing the attachment of the opening means I employ to open the said envelope.

Figure 2 is a view illustrating a portion of 30 envelope and the opening cord as the same appears before being secured in its proper position.

Figure 3 is a sectional view illustrating how the cord appears when embedded in the 35 envelope.

Figure 4 is a detail view showing the cord as placed in its proper position but with the sealing flap open.

Similar numerals of reference designate 40 corresponding parts in all of the views of the drawings.

My invention comprises the envelope body 1 that is provided with the longitudinal 45 meeting edges that are sealed or otherwise secured together as illustrated, and at one end the said envelope is provided with the flap 2, that is gummed so as to permit of ready sealing of the flap to the envelope body.

50 At its opposite end from the flap 2, the envelope is provided with the tabs or retaining strips 3, that are by preference formed

integral with the body 1, and as clearly shown in Figure 4, I secure a cord or other cutting member 4, under one of the tabs 3, 55 and extend the same along the end of the envelope and then pass the said cord under the other of the tabs or retainers 3.

At its extreme end opposite the flapped end 2, I provide a flap 5, that is integral with 60 the body 1, and is also gummed or otherwise provided with adhesive as illustrated.

Near its upper end the flap 5 is provided with an aperture 6, and the said aperture will permit of the ready handling of the 65 string 4 when the flap 5 has been pasted or otherwise stuck to the body 1.

In the practical use of the device, the cord 4 is placed under the tabs 3, and the end 2 is sealed to the body 1, and then a letter or 70 other communication is placed in the envelope in the ordinary well known manner. The flap 5 is then sealed to the body 1 and by this sealing process the cord will be securely held in the end of the envelope. 75 When a person desires to open the envelope, he simply takes hold of the cord through the opening 6 of the flap 5, and pulls the cord downwardly along the edge of the envelope, from the upper tab 3, to the lower tab 3. 80

It will be apparent from the foregoing that the envelope constructed along the foregoing lines differs very slightly from the ordinary well-known envelope, and is as easily used as envelopes now on the market. Moreover, the liability of tearing the contents of 85 said envelope is absolutely overcome, and the envelope as a whole presents the same appearance of the commercial envelope being used at present.

I would distinctly have it understood that the flap 5 and the flap 2 may be placed along the lower and upper edges of the envelope as well as along the ends of the envelope as illustrated by the drawings.

Having described my invention, what I claim and desire to secure by Letters Patent is:

In means for the purpose set forth, the combination of an envelope body, a flap arranged integral on the end thereof, tabs formed integral on said end of the body near the upper and lower edges thereof, a cord that passes under and from one to the other

of said tabs, one end of the cord being secured under one of the tabs, and an aperture in the flap under which the cord rests when the flap is secured to the envelope body, said aperture being arranged adjacent one of the tabs but out of registration with the tabs.

In testimony whereof I have hereunto set

my hand in presence of two subscribing witnesses.

JOHN J. McDERMOTT.

Witnesses:

L. McCORD,
PRENTICE E. EDRINGTON, Jr.
